UNITED STATES PATENT OFFICE.

PETER F. QUINN, OF RACINE, WISCONSIN.

TARGET.

Application filed December 28, 1923. Serial No. 683,193.

To all whom it may concern:

Be it known that I, PETER F. QUINN, a citizen of the United States, residing at Racine, in the county of Racine and State of Wisconsin, have invented a new and useful Target, of which the following is a specification.

This invention relates to targets and more particularly to those of the movable type capable of being toppled over by a well aimed shot.

The object of the invention is to provide a simple and efficient device of this character in which the targets are so constructed as to be toppled over by a shot and to automatically right themselves before coming again within range of the marksman.

Another object is to provide a wheel or disk carrying swingably mounted target units and so balanced as to spin rapidly by grasping it and giving it a quick turn in a manner similar to a wheel of fortune.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:

Figure 1 represents a front elevation of a target constructed in accordance with this invention with parts broken out to disclose the interior.

Fig. 2 is a similar view of the revoluble wheel which carries the target units, some of which are shown in toppled over position, the shaft on which the wheel rotates being shown in section.

Fig. 3 is a side or edge view of the target.

Fig. 4 is a transverse section through the supporting base and the axle with the front board supporting standards shown in elevation.

Fig. 5 is an enlarged detail side elevation of a portion of the revoluble wheel, showing one of the target units in operative position thereon; and

Fig. 6 is a detail sectional view taken on the line 6-6 of Fig. 1.

In the embodiment illustrated a base plate

1 is shown designed to be fixedly mounted on a suitable support and from which at the front thereof rises two standards 2 and 3 converging toward their upper ends and having mounted thereon a bearing 4 in which one end of an axle 5 is supported the other end being mounted in an upright back board 6 which is secured to the base plate 1 by upstanding lugs 7 preferably made integral with said plate.

A front board or wall 9 is mounted in front of the standards 2 and 3 and secured thereto by U-shaped clamps 8 any desired number of which may be employed and which extend through the board 9 and straddle the standards 2 and 3. A revoluble wheel 10 is mounted on the axle 5 between the front and back boards on ball bearings which permit the wheel to spin rapidly when a turn is imparted thereto. Carried by the perimeter of this wheel 10 are a plurality of target units 11 any desired number of which may be employed six being here shown. These units 11 may be of any desired configuration representing deer, bears, tigers and the like and which are hingedly mounted on plates 12 fixed to the front face of the wheel rim 13. The units 11 being of a thickness to adapt them to rest on the periphery of the wheel when in upright operative position the hinge connecting them with the plates 12 being located adjacent the front face of the wheel so that when one of the units is struck by a ball or other projectile it will topple over into the position shown at the right of Fig. 2. The representation of animals constituting a part of the unit 11 are shown mounted on a plate 14 which is hinged to plate 12 as shown in Fig. 5 and the weight of the target unit when the wheel moves downward or rather when the target itself moves down will cause it to swing by gravity over the periphery of the wheel in which position it will remain when the wheel turns carrying the units up in front of an arcuate slot or opening 9^a formed in the front board 9. This opening 9^a is concentric with the periphery of the wheel and has its lower wall 9^b positioned to register with the periphery of the wheel so that when the unit 11 carried by said wheel is moved into upward position or

105 position opposite the opening 9^a the entire unit will be visible throughout the length of the opening and may be shot at by the marks-

man and when struck by the projectile will topple over into the position shown at the right of Fig. 2 in which position it will remain until it reaches the lowermost point of the wheel shown at 15 in Fig. 2.

From the above description it will be obvious that a target constructed in accordance with this invention will be extremely simple having no gears, springs or similar parts to get out of order and owing to the simplicity of the structure it may be very economically constructed.

The front board 9 preferably has arranged on its outer face the representation of a jungle or thicket so that as the wheel spins the animals will appear to move up out of the thicket before the opening 9^a where they become visible to the marksman.

The back or rear board 6 is also preferably provided on its front face opposite the opening 9^a in the front board with the representa-

tion of the woodland scene to form a background for the animals passing in front of it.

I claim:—

A target comprising a revolvably mounted wheel having a plurality of spaced target units hingedly mounted on its perimeter to swing over the periphery thereof, a board mounted in front of said wheel having an arcuate opening with its inner wall registering and concentric with the periphery of the wheel and throughout the length of which the full target units are visible on the turning of the wheel.

In testimony that I claim the foregoing as my own, I have hereto affixed my signature in the presence of two witnesses.

PETER F. QUINN.
